UNITED STATES PATENT OFFICE.

ERNEST TIMMERHOFF, OF ELKHART, INDIANA, ASSIGNOR OF ONE-HALF TO CHARLES E. TEED, OF ELKHART, INDIANA.

BUFFER.

1,275,500.

Specification of Letters Patent. Patented Aug. 13, 1918.

Application filed July 26, 1917. Serial No. 182,950.

To all whom it may concern:

Be it known that I, ERNEST TIMMERHOFF, a citizen of the United States, residing at Elkhart, in the county of Elkhart and State 5 of Indiana, have invented certain new and useful Improvements in Buffers, of which the following is a specification.

This invention relates to an anti-rattling construction for automobile hoods, comprising particularly a means to be removably arranged in or on the hood-supporting flanges of the radiator and cowl, to receive the bearing edges of the hood, and prevent 10 play or rattle of such hood when the vehicle 15 is in motion.

The radiator and cowl flanges for the hood bearing have been heretofore provided with an anti-rattling means, in the form of a fabric or other strip laced or threaded 20 through openings formed in the flanges. This form of device is objectionable in that the lacing is somewhat difficult to apply, is somewhat expensive, in requiring entire renewal when broken, but more particularly, 25 in that the lacing is of equal thickness throughout, and is not thoroughly effective when the hood joints become worn, and greater play permitted in one part than in another.

30 The present invention is designed to provide anti-rattlers adapted for connection to the radiator and cowl flanges in a particular manner, so that an effective and more or less snug bearing is provided when the 35 hood is in place, the mounting of the elements permitting their independent removal or replacement, and also their adjustment to compensate for any looseness in any particular part of the hood. The simplicity of 40 the structure, together with its continued effectiveness under varying conditions of wear, renders it preferable to the present practically universal means for the purpose.

The invention, in the preferred form of 45 details, is illustrated in the accompanying drawings, in which:

Figure 1 is a broken perspective view, illustrating the application of the improvement.

50 Fig. 2 is an enlarged plan of a portion of one of the flanges, showing the opening therein for receiving the bumper-block.

Fig. 3 is a perspective view of the bumper-block.

Fig. 4 is a section through the flange, 55 showing the form of the opening.

Fig. 5 is a sectional view, showing the bumper block in position, and the hood bearing thereon.

The invention consists in applying a series of bumper-blocks, hereinafter termed bumpers, to the flanges of the radiator and cowl, preferably by seating said bumpers in openings formed in such flanges, the bumpers extending above the flange-surfaces to receive the corresponding edges of the hood.

The bumpers are to be arranged in any desired number, and the openings in the flanges are preferably formed to frictionally receive and hold the bumpers. As here shown, the said openings 1, are formed by punching the flanges at appropriate points, which results, as is intended, in a rough annular depending portion 2, forming the 70 marginal wall for the opening. The bumpers, which are preferably rubber blocks of cylindrical form, as at 3, are applied by forcing them into the openings. The relative size of the bumpers and openings, insures a frictional grip or fit of the bumpers 75 in the openings, thus fixing them for service, and against accidental displacement.

The bumpers act, as is obvious, to provide 80 a more or less resilient bearing for the edge of the hood, thus preventing rattling of the hood when the vehicle is in motion. Any 85 bumper may be readily replaced when worn or lost, no tools or particular skill being required for the operation.

It is of course not new to provide a rubber block where necessary to act as a buffer or bumper, and no claim is made to such herein, but it is believed that the advantage 90 of the structure herein shown and described, 95 for the particular use noted, is important.

Hoods are usually made in sections, connected for hinge action, and the connection becomes worn in use. Therefore, greater play results in one section of the hood. 100 With the lacing type of anti-rattler, an undue looseness of one part of the hood cannot be taken care of, as the lacing is of the same thickness throughout. With the present means, however, any one or more 105 of the bumpers may be readily and quickly adjusted in its particular opening, to take up the additional play of the hood section.

In other words, the present invention provides a means whereby the hood may be caused to bear against the anti-rattlers, without regard to unevenness of the hood bearing, and this of course insures the continued effectiveness of the present improvement.

Having thus described the invention, what is claimed is:—

1. The combination with the engine-hood supporting flanges, of independent resilient bumpers secured at spaced points in openings in said flanges, said bumpers being independently variable as to projection beyond the flange.
- 10 2. An anti-rattler for automobile engine-hoods, comprising a metallic support for the hood, and a resilient block to be secured frictionally in an opening formed in the metallic support, said opening being punched 20 to provide an edge wall below the opening to support the block.

3. An anti-rattle for juxtaposed members comprising a supported member, a supporting member having an opening therein, and a resilient bumper secured in said opening 25 and variable as to projection beyond said member, said opening being of a size to constrict the bumper at the point of contact with the edge forming the opening, and the bumper overlapping both sides of its supporting member beyond said opening.

4. An anti-rattle for juxtaposed members comprising a supported member, and a supporting member having an opening therein, and a resilient bumper secured in said 35 opening and variable as to projection beyond said member, said opening being of a size to constrict the bumper at the point of contact with the edge forming the opening.

In testimony whereof I affix my signature. 40

ERNEST TIMMERHOFF.
